UNITED STATES PATENT OFFICE.

FRANCIS CAMERON WESTMAN, OF TORONTO, ONTARIO, CANADA.

ICE-SCORING MACHINE.

Application filed August 6, 1927. Serial No. 211,128.

This invention relates to an ice scoring machine, as described in the present specification and illustrated in the accompanying drawings which form part of same.

5 The invention consists essentially of the novel features pointed out broadly and specifically in the claims for novelty following a description containing an explanation in detail of an acceptable form of the invention.

10 The objects of the invention are to build an ice scoring machine of simple, durable and economical construction; to effect all possible economy of space by making a very 15 compact and complete machine; to make the operation in such a machine as simple and reliable as possible; and generally, to improve upon existing ice scoring machines.

15 In the drawings, Figure 1 is a front elevation of the machine.

Figure 2 is a section on line 2—2 in Figure 1.

20 Figure 3 is a fragmentary side elevation of the sprocket chain showing the special link 25 and bridge.

Figure 4 is a top plan view of Figure 3.

Figure 5 is a fragmentary view showing the ice block feeding or shifting means.

25 Like numerals of reference indicate corresponding parts in the various figures.

Referring to the drawings, 10 is the frame of the machine; the frame is made of two end upright members 11, preferably castings, rigidly secured in their spaced relation by 30 spacers 12 and 13, and by the longitudinal members or beams 14 which are positioned in the axis of the machine. 17, 17^A, and 18 are sprockets rotating in the end members 11, each of the sprockets 17 rotating with the 35 gear 19 meshing with the gear 20 rigidly mounted on the horizontally-arranged shaft 21; the shaft 21 rotates in suitable bearings 21^A. 22 are sprocket chains wound around the sprockets, as best shown in Figures 1 and 2; the sprockets are disposed in a rectangular arrangement, as best shown in Figure 2, so that the sprocket chains travel in a substantially rectangular path.

40 23 is a motor mounted on the bracket 24 and rotating the horizontally-arranged shaft 25, on one end of which is rigidly mounted the pulley 26. 27 is a pulley rigidly mounted on one end of the shaft 21, and 28 is a belt wound around the pulleys 27 and 26. 45 29 are the scoring saws or elements rigidly mounted on the shaft 25 in any suitable way,

By operating the motor, the saws are rotated, the shaft 21 also rotated, turning the gears 19 and the sprockets 17 and therefore propelling the sprocket chains 22 in an endless course or path around the sprockets. 60

Pivotedly suspended from the sprocket chains 22 are the elevators, cradles or carriers 30 by which the ice block is carried; each elevator rises vertically to bring one face of the block in contact with the revolving saws, thus scoring that face, and later descends to bring the opposite or unscored face of the block in contact with the saws to score the last-mentioned face of said block. 70 The elevator is formed substantially as shown, having the spaced longitudinally-arranged members 31 secured to the tension members or supporting arms 32 by means of the bolts 32^A. Each of the arms 32 is 75 formed with a suitable eye 33 to pivotally connect the arm to the stud or pin 34 of the sprocket chain specially-formed link 35. The link 35 rigidly carries the bridge member 36 which is approximately twice as long 80 as the distance between the upper sprockets 17 and 17^A, thus forming a bridge between these sprockets and taking the load or weight of the elevator and ice off the chains when the links 35 are in any position between said sprockets, or in other words, when the elevator is travelling horizontally between the sprockets 17 and 17^A. 37 are cross members rigidly carried by the members 31 and spaced at a distance less than the length of the ice 90 block; near each end of the cross members are sharp pins or points 38 forming supports for the ice, and therefore digging into the ice block and preventing it from slipping. 95

The elevators are disposed along the chains so as to balance, as much as possible, the weight of one with that of the other.

40 40 are bars vertically arranged by bolting same to the bars 12 and 13 at a distance 100 apart less than the length of the block of ice, these bars forming slides or guides for the block as it travels upwardly and downwardly during the scoring operation, or in other words, constraining the movement of the block during scoring to two planes parallel with the chains 22.

41 are a pair of U-shaped irons suitably secured to the beams 14, forming stops checking the motion of the ice block as it is pushed 110 or fed into the machine prior to scoring, and also forming guides with the guides 40.

46 are horizontally-arranged bars bolted to the U-irons 41 and laid at right angles to the axis of the machine, one end of the bars being bent downwardly and inwardly as at 5 47; 43 is a plate supported by the angle irons 42 which are secured to the end castings 11 of the frame 10, this plate forming a table for the ice block as it is slid endwise into the feeding position, and also forming with 10 the bars 46 the means of supporting the block before it is engaged and lifted by the rising cradle 30 for the first scoring operation. The plate 43 and bars 46 are spaced from one another to provide a clearance 48 for the 15 passage of the bars 31 of the cradle 30. Bars 54 having the turned down ends 54^A are carried by the floor 43 and spaced opposite the bars 46, thus guiding the cradle bars 31 into the clearance 48. An angle 44 having 20 the turned out end 45 is preferably provided on the plate or table 43, so as to guide the ice when slid into feeding position in front of the machine; 50 is a suitable stop for arresting the motion of the block when 25 pushed in over the table, this stop also determining the position of the block from which it is to be fed into the machine.

53 is a suitable table secured to the frame, as with angles 55; a suitable slide is provided 30 to elevate the block from the cradle, after scoring, and allowing it to slide down onto the table 53; this slide and table forming the ice delivery means of the machine. The slide may be formed with metal-shod wooden wedge-shaped blocks 56 and 57 secured to the bars 46 and plate 53, respectively, these blocks being spaced to provide a clearance 58 for the passage of the cradle bars 31 as the cradle travels downwardly. 51 and 35 52 are guide bars vertically arranged and secured in position in any suitable way; in the drawings, the bars 51 are shown bolted to the cross bar 51^A which is rigidly secured to one of the beams 14, 60 being an angle 40 brace securing the lower ends of the bars 51 to the longitudinally-arranged bar 61 carried by the U-bar 41; the guide bars 52 are shown secured to cleats 62 carried by the braces 13 and also suitably fastened at the 45 bottom to the plates 43 and 53.

63 is a pivoted lever suitably journalled in one of the angles 42 and having a quadrant 64 rigid therewith; 65 is a horizontally-arranged shaft suitably journalled in the 55 angles 42 and having a quadrant 66 meshing with the quadrant 64; 67 are arms rigid on the shaft 65 and sized to extend to slightly beyond the angle 44 of the table 43, slots 68 being provided through the angle 44 to 60 form a passage for the ends of the arms as these are swung outwardly into operative position; the operative position of the arms 67 or lever 63, is determined by the engagement of the arms with the angle 44, or in 65 any other suitable way.

As the chains describe a substantially rectangular path, rising and lowering in vertical parallel planes, it follows that the clearances 48 and 58 must be vertically below the pivotal point of the cradle on the chain. 70

Operation: As already explained, the operation of the motor rotates the saws 29 while rotating the shaft 21 and propelling the chains 22. As the chains are propelled, in the direction of the arrow (Figure 2), the cradle describes a rectangular path. The unscored ice block is pushed upon the table 43, sliding against the angle 44 until it is arrested by the stop 50. The lever 63 is then pulled away from the machine, the arms 67 slidably engaging one face of the block and sliding same over the table 43 and onto the bars 46 until it comes in contact with the irons 41. The block is now in a position to be engaged or lifted by the cradle as it 80 travels up through the passage 48. One face of the block is scored as the cradle travels upwardly; as the cradle travels horizontally between the sprockets 17 and 17^A, the bridges 36 take the weight of the cradle and ice off 90 the chains and transfer same to the sprockets; as the cradle descends, the other or unscored face of the block is scored, and as the cradle passes through the clearance 58, the block becomes supported by the slide and finally slides out of the machine onto the table 53. 95

If the tables 43 and 53 are made level with the floor, a trough is made into the floor below the machine frame to provide clearance for the passage of the cradle as it swings under the machine. 100

It is to be understood that the invention is not confined to the particular construction shown, nor to the use of two cradles. Similarly, the invention is not confined to the use of a table 53, or of a table 43, since the ice could be slid over the floor and into the machine, and discharged at the delivery side onto the floor. 105

What I claim is:

1. In an ice scoring machine, scoring elements, an ice carrier travelling in a substantially rectangular path around said scoring elements and scoring the ice on opposite faces thereof, means for supporting the unscored ice prior to being raised by said carrier, and means for delivering the scored ice. 115
2. In an ice scoring machine, scoring elements, an ice cradle travelling in a substantially rectangular path around said scoring elements and rising to score one face of the ice and lowering to score the other face thereof, means for supporting the unscored ice prior to being raised by said cradle, and means for delivering the scored ice. 120
3. In an ice scoring machine, a frame, a pair of endless chains travelling in a substantially rectangular path, a cradle for the ice block pivotally suspended from said 125 130

- chains, scoring elements mounted in said frame and positioned to be in the path of the ice so as to successively score the opposite faces thereof, means carried by said frame and positioned to be slidably engaged by the ice during the scoring operation, means for supporting the ice prior to being raised by said cradle, and means for delivering the ice after scoring.
4. In an ice scoring machine, a frame, a pair of endless chains travelling in a substantially rectangular path, a cradle for the ice pivotally carried between said chains, scoring elements mounted in said frame and lying in the path of the ice, means for constraining the movement of the ice during scoring, means for supporting the ice in the path of said cradle, and means for delivering the ice after scoring.
5. In an ice scoring machine, a frame, sprockets rotatable in the ends of said frame and disposed substantially in rectangular arrangement, sprocket chains wound around said sprockets, a cradle for the ice pivotally suspended from said chains, scoring elements mounted in said frame and lying in the path of the ice when said cradle rises and lowers, means for operating said scoring elements and sprockets, means adapted for taking the weight of said cradle off said chains as the cradle travels horizontally between the uppermost of said sprockets, means for supporting the ice before being raised by said cradle, and means for delivering the ice after scoring.
6. In an ice scoring machine, means adapted for supporting the ice prior to the scoring operation, arms pivotally mounted adjacent said means and adapted to slidably engage one face of the ice block when said arms are swung inwardly, a shaft rigidly mounting said arms and having a quadrant rigidly secured thereon, and a lever-operated quadrant meshing with said first-mentioned quadrant.
7. In an ice scoring machine, a frame, a shaft journalled in said frame, scoring saws mounted on said shaft, means for actuating said shaft, sprockets rotatable in the ends of said frame, chains wound around said sprockets, one of said sprockets at each end having a gear rigid therewith, a shaft having gears rigid therewith meshing with said first-mentioned gears, means for rotating said last-mentioned shaft with said first-mentioned shaft, a cradle for the ice pivotally suspended from said chains, means for supporting the ice before scoring, and means for delivering the ice after scoring.
8. In an ice scoring machine, a frame, a shaft journalled in said frame, scoring elements mounted in said shaft, means for actuating said shaft, sprockets rotatable in the ends of said frame and disposed in substantially rectangular arrangement, chains wound around said sprockets, one of the uppermost of said sprockets in each end of said frame having a gear rotating therewith, a shaft adjacent the top end of said frame having gears rigid therewith meshing with said first-mentioned gears, means for rotating said last-mentioned shaft with said first-mentioned shaft, a cradle carried by said chains for raising and lowering the ice into the path of the scoring saws, means for supporting the ice before scoring, means for delivering the ice after scoring, and means in said chains adapted for taking the weight of said cradle off said chains as the cradle travels horizontally between the uppermost of said sprockets.
9. In an ice scoring machine, a frame, sprockets mounted in said frame and disposed in substantially rectangular arrangement, chains wound around said sprockets, said chains having each a link carrying a bridge member therewith adapted to take the weight of said cradle off said chains as the cradle travels horizontally between the uppermost of said sprockets, scoring saws lying in the path of the ice, means for actuating said chains and saws, means for supporting the ice before scoring, and means for delivering the ice after scoring.
10. In an ice scoring machine, a frame, sprockets mounted in said frame and disposed in substantially rectangular arrangement, chains wound around said sprockets, said chains having each a link rigidly carrying a member of a length exceeding the distance between the uppermost of said sprockets, scoring saws lying in the path of the ice, means for actuating said chains and saws, means for supporting the ice before scoring, and means for delivering the ice after scoring.
11. In an ice scoring machine, scoring elements, an ice carrier travelling in a substantially rectangular path around said scoring elements and scoring the ice on opposite faces thereof, means for constraining the movement of the ice during scoring, means for supporting the unscored ice prior to being raised by said carrier, and means for delivering the scored ice.

Signed at the city of Toronto, this 18th day of July, 1927.

FRANCIS CAMERON WESTMAN.
